DOOR LATCH

Frank L. Aumack, Spokane, Wash., assignor to John G. Rotchford, as trustee, Spokane, Wash.

Application March 4, 1938, Serial No. 193,955

3 Claims. (Cl. 292—340)

My present invention relates to improvements in door latches and the invention essentially embodies an anti-rattling device that automatically renders a closed door rattle-proof. The invention is adapted for use with various kinds of closure-fasteners, but is especially designed as an anti-rattling device employed in connection with house door latches or fastenings to hold the door tightly closed in weather-proof position against the door-stop. The automatic anti-rattling device is also applicable for use with the latch-bolts of doors for automotive vehicles, to prevent rattling of the door that would otherwise be occasioned by vibrations of the traveling vehicle.

The invention embodies an automatically operating ball-detent that is seated in an opening of the latch-plate of the door-jamb, which detent co-acts with the free end of the door latch or latch-bolt carried by the door, to hold the door in rigid closed position. When the door is open, or the latch is withdrawn, the ball-detent automatically moves into the path of the latch and rests in a seat in the stationary latch-plate. As the door is closed, and its projected latch-bolt contacts the ball-detent, the latter is unseated, and thereafter the free-moving ball-detent automatically returns to contact with the latch, and is finally re-seated, with a wedging action against the latch, to hold the latter rigidly in closed position.

The closed latch is thus automatically tightened, and the door is consequently rigidly held against rattling, and in close contact with the door-stop.

The ball-detent, of course, operates in such manner as not to impair the efficiency of the latch in its usual functions and on the other hand, the anti-rattling device of my invention in the performance of its functions compensates for wear on the latch bolt and its supporting parts and automatically adjusts the bolt to its closed position.

The invention consists in certain novel combinations and arrangements of parts as will hereinafter be more fully set forth and claimed. In the accompanying drawing I have illustrated one example of the physical embodiment of my invention wherein the parts are combined and arranged according to the best mode I have thus far devised for the practical application of the principles of my invention.

Figure 1 is a top edge view of the stationary latch-plate removed from the door-jamb, showing

the caged ball-detent occupying its seat, as when the door is open.

Figure 2 is a face view of the latch-plate, showing particularly the ball-seat in the slotted plate.

Figure 3 is a vertical sectional view of the latch plate showing the cage in section, and the ball-detent in its seat.

Figure 4 shows the ball just after it has been unseated by the passing latch, the jamb, cage, latch-plate, door and door-stop being shown in section.

Figures 5 and 6, successively, show positions of the automatically returning ball, after passage of the latch to closed position, and Figure 7 shows the ball-detent wedged against the latch-bolt, and the door is thereby held rigidly against the door-stop.

Figure 8 discloses a spring-retumed ball-detent, as distinguished from the gravity-retumed ball-detent.

In order that the general arrangement and utility of parts may be readily understood I have shown portions of a hinged door D, and its door-stop S, and a typical sliding or reciprocating latch-bolt L is mounted as usual in the door, said latch-bolt having the usual rear straight face F, and the cam front-face F'.

The usual door jamb is indicated as J, and the door stop S, as well as the metal latch-plate P are rigid with the jamb, the plate P being screwed as usual to the jamb through holes 1, 1.

The latch plate is provided with the usual slot 2 for the locking bolt, and also with the usual slot or aperture 3 for the latch-bolt L. In converting the latch-plate for use with my invention a cage or housing 4 is secured, as by spot-welding or in other suitable manner, to the inner or rear face of the plate and in the gravity-actuated or gravity-retumed device of Figures 2 and 3, it will be seen that the cage or housing inclines upwardly from the plate, and it also extends backwardly from the aperture 3 of the plate.

Within the cage or housing is confined a ball-detent or metal sphere B, and the upper rear end of the cage is provided with a retaining flange or stop 5 to prevent displacement of the ball through the rear open end of the cage. At its junction with the plate P, the cage is fashioned with a lateral aperture 6 that opens into the mortise or recess J' of the jamb, and this mortise is aligned with the slot 3 for the reception of the latch L. The cage at its junction with the plate is also fashioned with a circular

aperture 7 that opens to the slot 3, and this aperture forms a seat for the ball B, the apertures 6 and 7 being smaller in diameter than the diameter of the ball-detent, in order that the ball may partially project through the apertures, but the ball is prevented from passing entirely through either of the apertures.

In Figures 1 and 3 the ball-detent is shown seated in the aperture or seat 7, and projecting 10 slightly through the lateral aperture 6, and this is the position occupied by the ball B when the door is opened, or when the latch L is withdrawn. The ball is free to roll within its cage, and because of the combined downward slant, 15 as in Figure 3, and the lateral incline seen in Figures 1 and 4, the ball, by gravity, automatically finds its seat, as in Figures 1 and 3.

When the door approaches the end of its closing movement the cam face F' of the latch first 20 wipes against the ball and unseats it, the wiping action impelling the ball to position of Figure 4. After the point of the latch has passed across the seat 7 and snapped into the mortise, the ball rolls down the cage under gravity, encountering 25 the point of the latch as in Figure 5, and as the door is pulled or pushed to its final closing position the ball slips in between the face F of the latch and the rear wall of the cage, as indicated in Figure 6. The final movement of the ball 30 wedges the latter in between the straight face F and the rear wall of the cage as in Figure 7, where the door is shown snugly engaging the stop S, and the latch is wedged between the ball and the front wall of the slot 3 of the plate. The ball 35 on the other hand is wedged with a slight frictional engagement in between the latch and the rear wall of the cage.

The door may be opened in the usual manner by turning the latch handle for the purpose of withdrawing the latch from its wedged position 40 in the mortise. As the latch is thus retracted its frictional contact with the ball causes the latter to turn clock-wise in Fig. 7 thus releasing the wedge, and as the unlatched door is swung to open position, the ball detent rolls into and re- 45

mains in its seat, to be again unseated when the door is again swung to closed position.

In Figure 8 I disclose the use of a spring 8 interposed between the ball and a retaining flange 5 of the cage 4, which spring may be employed in 5 lieu of gravity for returning the ball to its seat 7. In the use of the spring-retumed ball B the cage 4 need not necessarily be inclined as in Figure 3, and the cage may be arranged at the lateral angle of Figure 1, and the ball-detent performs the 10 same functions in the construction of Figure 8, as in the other figures of the drawing.

Having thus fully described my invention, what I claim as new and desire to secure by Letters Patent is:

1. In a door latching device, the combination with a latch-plate having a mortise-aperture, of a cage rigid with said plate, and a free rolling ball confined in said cage, said cage having a lateral opening merging with the mortise aperture, and 20 said cage also having a front seat-opening merging with the mortise-aperture.

2. In a door latching device, the combination with a latch-plate having a mortise-aperture, of a cage rigid with said plate, a freely rolling ball-detent confined within the cage, said cage being disposed at a lateral angle and also disposed at a vertical angle to the plane of the plate, said cage having a lateral aperture opening to the mortise-aperture and an end opening forming a front 30 seat also merging with said mortise-aperture, and said aperture and opening being of less diameter than the diameter of the ball-detent.

3. In a door latching device for use with a hinged door having a slide latch, the combination of a latch-plate having a mortise-aperture to receive the latch, of a cage mounted on the plate, a gravity-actuated ball-detent free to roll in one direction to latched position and positively moved in the opposite direction by contact with the 40 latch bolt as it moves toward projected position, said ball-detent being confined in the cage and said cage having a front seat and a lateral aperture merging with the mortise-aperture.

FRANK L. AUMACK.
